(57) **CLAIM**

I claim the ornamental design for a urinal, as shown and described.

DESCRIPTION

FIG. 1 is a perspective view of an embodiment of the claimed design;

FIG. 2 is front view of the embodiment of FIG. 1;

FIG. 3 is a rear view of the embodiment of FIG. 1;

FIG. 4 is a side view of the embodiment of FIG. 1;

FIG. 5 is another side view of the embodiment of FIG. 1;

FIG. 6 is a top view of the embodiment of FIG. 1; and,
FIG. 7 is a bottom perspective view of the embodiment of FIG. 1.

The ornamental design which is claimed is shown in solid lines in the drawings. The broken lines formed of equal length dashes in the drawings show portions of the urinal that form no part of the claimed design. Broken lines formed of unequal length dashes (i.e., dash-dot) define the boundary of the claimed design and form no part of the claimed design.
